(57) **CLAIM**

The ornamental design for an outsole, as shown and described.

DESCRIPTION

FIG. 1 is a left side elevational view of an outsole showing my new design; the broken outline of a boot illustrating environment subject matter, forms no part of the claimed design;

FIG. 2 is a bottom plan view of the outsole design;

FIG. 3 is a front elevational view of the outsole design; and, FIG. 4 is a rear elevational view thereof.

FIG. 5 is a right side elevational view of the outsole showing my new design; and,

FIG. 6 is a bottom perspective view of the outsole showing my new design.

1 Claim, 5 Drawing Sheets

FIG. 2

FIG. 3

FIG. 4
